UNITED STATES PATENT OFFICE.

EDWARD M. HEYLMAN, OF SOUTH BEND, INDIANA, ASSIGNOR TO OLIVER CHILLED PLOW WORKS, OF SOUTH BEND, INDIANA.

WHEELED CULTIVATOR.

1,258,680.

Specification of Letters Patent. Patented Mar. 12, 1918.

Original application filed December 16, 1915, Serial No. 67,231. Divided and this application filed March 23, 1916. Serial No. 86,225.

To all whom it may concern:

Be it known that I, EDWARD M. HEYLMAN, a citizen of the United States, and a resident of South Bend, in the county of Saint Joseph and State of Indiana, have invented certain new and useful Improvements in Wheeled Cultivators; and I do hereby declare the following to be a full, clear, and exact description of the invention, such as 5 will enable others skilled in the art to which it appertains to make and use the same.

This invention relates to improvements in wheeled cultivators, this case being a division of application filed by me on the 16th 15 day of December, 1915 and designated by Serial No. 67,231.

One object of my present invention is to provide a seat construction for cultivators which may be easily shifted laterally with 20 slight exertion on the part of the operator, whereby the operator may be permitted readily to view the plants being cultivated.

A further object is to provide simple and efficient means whereby the laterally-shiftable seat construction may be readily adjusted, or be folded when the machine is operated as a walking cultivator.

With these and other objects in view, the invention consists in certain novel features 30 of construction and combinations of parts as hereinafter set forth and pointed out in the claims.

In the accompanying drawings,—Figure 1 is a plan view of a cultivator embodying my improvements; Fig. 2 is a side elevation; Fig. 3 is an enlarged view on the line 3—3 of Fig. 1; Fig. 4 is a plan view of the structure shown in Fig. 3; Fig. 5 is a fragmentary plan view showing the mounting of the 40 seat frame on the arch axle; Fig. 6 is a sectional view on the line 6—6 of Fig. 5, and Fig. 7 is a side elevation of the structure shown in Figs. 5 and 6, with the arch axle shown in section.

45 1, 1, represent the frame bars having their forward portions bent toward each other and connected at their forward ends by means of a bracket 2,—a tongue 3 being pivotally connected with the latter, as at 4.

50 The rear ends of the bars 1 are rigidly connected with a horizontal tubular bar 5, through the medium of sleeved brackets 6,—said bar constituting the rear end of the frame and also forming, in effect, a portion

of a rear arch axle, the respective members 55 7, 7, of the latter being mounted in said tubular bar and in the hubs of carrying wheels 8.

The pole 3 is provided with a rearward extension 9 (which may comprise two metal 60 bars 10—11 secured to the upper and lower faces of the tongue and secured together rearwardly of the tongue, as shown at 12 Fig. 3) and with said rearward tongue extension, a front arch 13 is connected through 65 the medium of a coupling 14 which is keyed to said arch and pivotally connected with the tongue extension 9, as shown in Fig. 3. The lower ends of the respective members 70 of the front arch 13 are made with laterally 75 projecting horizontal arms 15, for attachment of cultivator gang frames 16. In effecting such connections between the gang frames and the arms of the front arch, couplings 17 are mounted on said arch arms 75 and with these couplings, the gang frames are pivotally connected by vertical pivots as shown at 18. The pivotal connection between the gang frame and coupling is located near one end of the latter and a rod 80 85 19 is attached to said coupling near its other end.—the rear end of said rod being threaded and adjustably connected with a bracket 20 secured to and projecting laterally from the gang frame,—such construction affording means for adjusting the gang frames laterally.

An evener bar 21 is pivotally connected between its ends to the tongue 3 and with 90 respective ends of said bar, depending draft equalizers 22 are pivotally connected. These vertical equalizer bars are adapted for the adjustable attachment of swingletrees 23, and at their lower ends, said equalizer bars 95 are connected with the arms of the front arch by means of suitable links 24. Brace bars 25 are attached at their forward ends to brackets 26 mounted on the front arch arms and extend rearwardly and upwardly therefrom, the rear ends of said brace bars 100 being attached to the brackets 6 at the rear end of the main frame.

I employ a seat frame comprising flat bars 67—67 disposed edgewise and connected at their forward converging ends by a bracket, 105 68, said frame bars being separated somewhat forwardly of their rear ends by a cross bar 69,—which latter is mounted over the

arch axle as presently explained. The rear ends of the bars 67 are bent downwardly to form depending arms 70, each having a series of perforations 71. The forward ends 5 of seat arms 72 are pivotally connected with the bars 67 forwardly of the depending arms 71 and adjustably support a seat 73. The seat arms and the seat are adjustably supported by bolts 74 passing through any of 10 the series of perforations in the depending arms 70. By means of this construction the seat may be adjusted vertically to accommodate a particular operator and enable him to readily reach the stirrups 66 on the cultivator gangs. This construction also permits the seat to be folded over the machine out of the way when adjustment of the shovels become necessary or when it is desirable to convert the machine into a walking 20 cultivator.

A bracket 75 is clamped upon the intermediate tubular portion of the arch axle and is provided with a boss 76 to receive a hub 77 on the cross bar 69 and afford a pivotal mounting for the latter. A bolt 77^a passes through the boss 76 and is provided at its lower end with a head countersunk into the bracket 75,—the upper end of said bolt being threaded to receive a nut 78, between 30 which and the upper ends of the bars 76 and hub 77, a washer 79 is disposed. The cross bar 69 is made in its under side with elongated grooves or runways 80 for anti-friction balls 81 and the upper face of the bracket 75 affords trackways for these balls. 35 Stops 82 are provided on the bracket to prevent escape of the anti-friction balls.

The bracket 68 is provided in its rear portion with an elongated slot 83 in which a 40 roller 84 enters, said roller being carried by a pin 85 projecting upwardly from the tongue extension 9, and in this manner the forward end of the seat frame is loosely connected with the rear end of the tongue.

45 The bracket 68 is provided at its forward end with upwardly projecting arms 86 braced by a spreader 87, and in said bracket, (at the lower ends of the arms 86), a roller 88 is mounted. This roller is adapted to 50 run on a transverse bar 90 (disposed above the same) when the seat frame is swung laterally on its pivotal mounting. The transverse bar 90 is connected with the main frame bars 1, by means of brackets 91, and 55 the respective end portions of said transverse bar are connected, by means of rods 92 with brackets 93 on its lower horizontal arms of the front arch 13, as shown in Figs. 1 and 2.

60 It will be understood that when the operator is sitting upon the seat 73, his weight will be sustained upon the arch axle through

the intervention of the anti-friction balls, and that the roller at the forward end of the pivoted seat frame will press upwardly 65 against the transverse bar 90. When the operator forces the seat to the right or left, the cross bar 69 will pivot on the bracket 75 and the balls 81 will roll on the trackways afforded by the cross bar 69 and bracket 75, 70 while the roller 88 will rub on the transverse bar 90. Such construction reduces frictional resistance and renders easy the shifting of the wheels and shovel gangs for cultivating plants not planted in straight 75 lines, and by disposing the bars of the seat structure edgewise, the operator is enabled more readily to see the plants being cultivated.

A hook link 94 may be attached to one of 80 the brackets 91 and adapted to be connected with the front arch for locking the same against side movement, when the machine is being transported.

Various slight changes might be made in 85 the details of construction of my invention without departing from the spirit thereof or limiting its scope and hence I do not wish to restrict myself to the precise details herein set forth.

Having fully described my invention what I claim as new and desire to secure by Letters-Patent is:—

1. The combination with a wheeled frame, and a cultivator gang connected therewith, 95 of a seat frame including a transverse bar a horizontal bracket secured to the wheeled frame, means pivotally connecting the transverse bar of the seat frame and said bracket, anti-friction devices between said 100 transverse bar and bracket, a forward transverse bar secured to the wheeled frame, and a roller carried by the forward end of the seat frame and adapted to run on the under side of said forward transverse bar. 105

2. The combination with a wheeled frame and a tongue, of a pivotal connection between said forward portion of the wheeled frame and tongue, a seat frame pivotally mounted between its ends on the wheeled 110 frame, a loose connection between the forward portion of said seat frame and the tongue, a cross bar carried by the forward portion of the wheeled frame, and means on the forward portion of the seat frame movable on the under side of said cross bar. 115

In testimony whereof, I have signed this specification in the presence of two subscribing witnesses.

EDWARD M. HEYLMAN.
